(57) CLAIM

The ornamental design for a body brush, as shown and described.

DESCRIPTION

FIG. 1 is a front, top perspective view of a body brush showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of the circular region on the top of the body brush, the rounded trapezoidal region in the rear of the body brush, and the bristles represents environmental structure and forms no part of the claimed design.
